UNITED STATES PATENT OFFICE.

LEBBEUS H. ROGERS, OF NEW YORK, N. Y.

MANUFACTURE OF WINDOW-CURTAINS, LAMBREQUINS, AND OTHER ARTICLES FROM PAPER.

SPECIFICATION forming part of Letters Patent No. 268,539, dated December 5, 1882.

Application filed March 24, 1882. (No model.)

To all whom it may concern:

Be it known that I, LEBBEUS H. ROGERS, of New York city, in the county and State of New York, have invented a new and useful Improvement in the Manufacture of Window-Curtains, Lambrequins, and other Articles from Paper, which improvement is fully set forth in the following specification.

This invention has reference to the production from paper suitable for the purpose of window-curtains, lambrequins, and other articles having an irregular outline or configuration, the paper being perforated and scalloped by means of dies in imitation of lace, and to the method of folding the sheets of paper from which the articles are made, so that, no matter what may be the outline or direction of the pattern, the design can be produced by dies cutting in a straight line.

Tissue-paper ornamented in the manner described is useful for a variety of purposes, such as for ornamenting shelves or the interior of fancy boxes; but its production is comparatively expensive by reason of the high cost of the dies necessary to do the cutting, each different pattern of course requiring a different set of dies. The manufacture of ornamental paper has therefore been confined almost exclusively to patterns which run or are capable of being cut in a straight line—such as used for covering shelves, for example; and the process of production generally followed consists in feeding a number of sheets, or a single sheet folded on itself a number of times, in a straight line under the cutting-dies. Where it is desired to ornament in this manner the four edges of a square or rectangular sheet, instead of going around the four edges in succession with a straight die, it has been customary to fold the sheet upon itself in the middle, and then again upon a line at right angles to the first fold, bringing the four edges of the original sheet into two adjacent sides of the reduced sheet. The cutting is then done by an angular die corresponding to these two edges. This of course requires a special die. To produce, however, articles such as window-curtains, lambrequins, and the like, in which the line of pattern runs in different and irregular directions, though

which, in order to insure their introduction and use to a remunerative extent, there must be produced a large number of different styles to suit different tastes, it would be necessary to provide a special die for each shape of article 55 and for each design in which that shape of article is to be produced, which die would be useless for any other shape. The cost, therefore, of such a large number of dies would be so enormous as would make it impossible to dispose of the articles, when made, at a profitable rate. This is mainly the reason why no attempt has been made heretofore to produce articles of this description on an industrial scale.

The present invention therefore has for its object, first, to produce window-curtains, lambrequins, and similar ornamental hangings and room-decorations, and other articles having an irregular outline, from paper cut, scalloped, 60 and perforated in imitation of lace-work; and, second, to so fold the sheets of paper from which said articles are cut that the edges forming the outline of the same, no matter what their configuration may be, will all be made to 65 coincide, so that the cutting can be done by a straight die.

By the term "straight die," as used in this specification, is meant a die in which the direction of the pattern or design is a straight 70 line; and by the term "line of pattern" is meant all the broken lines which together make up the outline of the article to be ornamented, or all the edges or boundary-lines along which the design is to be produced.

The method of folding an article having an irregular line of pattern consists in successively folding the sheet at each angle formed by the line of pattern, or a line that bisects that angle. When the sheet has been so folded 80 at each of the angles made by the line of pattern it will be found that all the broken lines making up the outline of the figure will be brought into coincidence, so that the desired pattern can be cut by a straight die operating 85 in a straight line. When it is considered that by this method only the ordinary straight dies need be employed to produce designs that run in different directions, and that the same die 90 can be used for ornamenting articles of very 95

different outline, the advantages of the invention will be apparent, as it obviates the necessity of employing a large number of expensive dies, and enables articles of irregular outline 5 to be produced at a cost no greater than that of articles having a straight-ahead pattern.

In order the more fully to explain the said invention to enable persons skilled in the art to which it relates to make and use the same, 10 it will now be described in connection with the accompanying drawings, which form a part of this specification.

Figure 1 represents a window decorated with curtains and lambrequin made of paper 15 and ornamented in accordance with this invention, and Figs. 2 to 12 are diagrams illustrating the method of folding.

In Fig. 1, A represents the curtains, formed usually of white tissue-paper with its edges 20 scalloped, and having a design or pattern cut therein in imitation of lace. The lambrequin B, similarly ornamented, would, for the sake of contrast, be made ordinarily of colored paper. The imitation cornice C is of gilt paper. The color of paper, the character of the 25 design, and the configuration or outline can be indefinitely varied according to taste.

The method of folding the sheet to produce the lambrequin B (shown in Fig. 1) will be understood by referring to diagrams Figs. 2 to 30 6. Throughout these figures the line of pattern is represented by a heavy line and the lines of fold by broken lines. The first fold will be taken on line xx , Fig. 2, with the result shown in Fig. 3. Now, to bring the lines ab and ef , Fig. 3, forming part of the line of pattern, into coincidence with lines bc and de , folds are made on lines xx and yy , which respectively bisect angles abc and def . This 40 brings the sheet into the shape shown in Fig. 4. The next fold is taken on line xx , Fig. 4, which brings into coincidence the lines bc and de , as seen in Fig. 5. The sheet is now finally folded on line xx of Fig. 5, which bisects angle 45 gde , bringing all the broken lines which make up the outline of the lambrequin in Fig. 2 into one straight line, de , Fig. 6, along which line the die operates, and the article has simply to be unfolded and it is ready for use.

50 To ornament a lambrequin of the shape shown in Fig. 7, the sheet is first folded on line xx bisecting angle bcd , and then on lines yy and zz bisecting angles abc and cde .

To further illustrate the method of folding, 55 reference will now be had to Figs. 8 to 12. Fig. 8 represents a five-pointed star, the edges of which it is desired to scallop and perforate. The line of pattern is represented by a heavy line, as before. A fold is taken through line x 60 x bisecting angle a , Fig. 8, then on line yy

bisecting angle b , Fig. 9, then on line zz bisecting angle c , Fig. 10, and finally on line x x bisecting angle d , Fig. 11, which brings all the lines forming the outline of the figure into a single straight line, ef , Fig. 12, along which 65 the die operates. From these illustrations it will be seen that in order to perforate and scallop paper on an irregular or broken line it is only necessary to fold the sheet wherever the line of pattern makes an angle on a line 70 that will bisect that angle; and that the same straight die used to cut straight-ahead patterns can as well be employed to cut the pattern on the lambrequins, Figs. 1 and 7, and on the star, Fig. 8.

75 It will be observed that where an article is more or less symmetrical in outline it is by no means necessary to make a separate fold for each angle. Thus in the star represented in Fig. 8, although the line of pattern makes ten 80 different angles, only four folds are necessary to bring the outline into a single straight line.

It is obvious that, by following the rule given for folding the sheet to bring the line of pattern into one straight line, designs can be produced by the same straight dies in the interior 85 as well as on the outside edges of the sheet.

I am aware that heretofore articles of different shape have been cut by a single straight cut from paper or card-board so folded as to 90 bring all the boundary-lines of the figure or figures to be cut into coincidence, and different methods of folding have been pointed out whereby articles of different shape could be so produced; but such methods refer only to the 95 production of specific shapes, and are not applicable to any other, and they form no part of the present invention.

So far as I am aware, the method above described of folding paper to be operated on by 100 a straight die, and which is applicable to the production of articles of any desired symmetrical outline, has never heretofore been pointed out.

Having now fully described my said invention and the manner of carrying the same into effect, what I claim is—

Window-curtains, lambrequins, and similar articles having an irregular outline, made from paper perforated and scalloped in imitation of lace, substantially in the manner and by the means set forth.

In testimony whereof I have signed this specification in the presence of two subscribing witnesses.

LEBBEUS H. ROGERS.
